FLOAT-BOAT FOR CHILDREN

Sam Sonin, Kansas City, Mo.

Application July 6, 1954, Serial No. 31,298

Term of patent 14 years

(Cl. D71—1)

Fig. 1.

Fig. 2.

Fig. 3.

Figure 1 is a top perspective view of a float-boat for children showing my new design;

Figure 2 is a view of the same in side elevation; and

Figure 3 is an end view of said float-boat.

The float member encircling the bottom portions represents a rubber tube.

I claim:

The ornamental design for a float-boat for children, substantially as shown and described.
